UNITED STATES PATENT OFFICE

FRANK W. HENRIKSON, OF MULBERRY, KANSAS

CAR COUPLING

Application filed February 24, 1927. Serial No. 170,543.

This invention relates to improvements in coupling devices for assembling vehicles in trains, and is more particularly of the type employing dissimilar parts, one of such parts being provided with a link and the other with a cooperating pin.

Devices of this type have been disclosed, for example, in my Patents 1,587,229 and 1,587,230, issued June 1, 1926: and the present invention presents certain changes in such mechanism. While the invention may be employed with vehicles of any type, it is particularly adaptable for use on mine cars for automatic coupling with the corresponding member of another car. When employed with such mine cars it is particularly adapted for the automatic or semi-automatic operations of dumping and recoupling. A string of cars having couplings according to the 20 type of the present invention may be brought to a ramp leading to a dumping mechanism, and may be disconnected from train, one by one, as the individual car passes onto the ramp. The car may then pass down the 25 ramp, be received by the dumping mechanism, dumped and returned, and then permitted to run by a further ramp to a track on which the empties are assembled previous to being returned to the mine for further 30 loads. As each car approaches the last car in the string of empties, it is automatically coupled thereto, so that thereafter the entire train may be moved without further manual attention to the particular car.

This invention presents a device in which the vehicles may make turns or curves of very short radius without a blocking by the link in either drawhead. It may be applied to either old or new cars without any great 40 change in the construction.

The link member of the link drawhead is provided with an actuating mechanism whereby it is projected into the pin drawhead upon impact of the two cars: and positive guides are provided for the actuating linkage. Further a very stout construction is provided for the link drawhead so that the draft stresses are transmitted from draft beam to draft-beam without burden upon the 45 actuating mechanism. The link is reversi-

ble, and its drawhead is so constructed and arranged that reversal may be accomplished without dismounting.

Cushioning springs are provided so that the shock at impact may be employed to operate the actuating mechanism without undue strain thereon in the event of a blockage. 55

The invention has been illustrated as applied to mine cars of the four-wheel, short-base type; since with such employment its qualities of permitting the automatic pin-resetting, and the traversing of curves of very short radius are clearly apparent. 60

In the illustrative form of the invention set forth on the accompanying drawing: 65

Figure 1 is a plan view of a car having the coupling device associated therewith, and the cooperating ends of two further cars being indicated to show the draft system.

Fig. 2 is a detail view of the bumper stem 76 and associated parts.

Fig. 3 is a view of the other end of the car, showing the link member.

Fig. 4 is a longitudinal section through a link member on an enlarged scale. 75

Fig. 5 is a horizontal section substantially on line 5—5 of Fig. 4.

In these figures, the car is represented as having a floor 10, the sides 11 and the ends 12, 13. A truck 14 has suitable bearings to support the axles and wheels 15, 15. According to the present invention, a metal draft strip or beam 16 is fastened to the floor of a car to transmit the draft strain along the line of the train. Adjacent the end wall 12 a casting is provided having the plate 17 which is bolted to the floor 10 of the car and to the draft beam 16, and carries at its outer end the link draw head 18. At the opposite end, is disposed a similar casting having a plate 19, likewise bolted to the floor 10 of the car and to the draw beam 16, and having at the exterior of the car the pin drawhead 20. In Fig. 1, the similar 80 parts of the car at the left hand, i. e., a car presenting a link connection, are indicated by the same reference numerals with the suffix *a*, the corresponding link drawhead being 18^a, for example. The car at the right hand, having corresponding parts, is like- 90

95

95

95

100

wise given the same reference numerals with the superscript *b*, and this car therefore has the pin drawhead 20^b.

The drawhead 18 as shown in Fig. 3 has the laterally extending brace plates 18^a, to stiffen and support it at the car end beam 12^a. It is preferred to form the plates with reinforcing ribs extending transversely of the car, with the notches or kerfs 18^b therein to permit the brace plates to yield when bolted down, to afford a tight clamping relationship of the parts.

In Fig. 4, the car floor 10 with the draft beam 16 and the plate 17 thereon, has the several members secured together by the retaining bolts 21. The drawhead 18 is made in one piece and hollowed, and is formed with an integral bight 22 which closes its open end. Beneath the bight 22 is an actuating bumper 23 which is capable of movement longitudinally with respect to the draft beam and associated members. For this purpose, the bumper 23 has a square inwardly extending actuating stem 24 and the guide stems 25, these stems projecting through apertures in a depending flange 26 of the drawhead 18, and the stem 24 entering a cavity in the lower portion of this drawhead. A reduced portion 24^b of the stem 24 has a vertical slot 27 therein, and its end is received in a slot 29 of a rectangular actuating rod 30 which extends through a further aperture in the drawhead 18 and has its innermost end in contact with a cam 31 of the actuating lever 32. This actuating lever 32 is journaled on a pin 33 carried by the walls of the drawhead 18. A spring 34 is connected to a suitable part of the lever 32 at one end and at its other end is secured to a pin 35 fastened to the drawhead 18. At its upper end, the lever 32 has an aperture to accommodate the laterally extending end 36 of the actuating link 37, which may be riveted into position, and has at its other end a closed oblong or oval eye 38 with the rib 38^a, to receive the link L. This link L may be prepared in V-shape and passed through the eye 38 and around the bight 22, and then the ends welded together to close the link. This link slides freely in a channel formed in the drawhead 18, and is of a symmetrical closed form, and fits in the eye 38 and about the bight 22. When the strain is placed upon the link L in train, it is drawn forward until the link L comes into contact with the inner face of the bight 22, and thereafter the draft strain is transmitted from the link to the bight 22, thence to the drawhead 18, and to the car floor 10 and draft beam 16.

The eye 38 closely fits the link L for movement back and forth, while permitting a free swinging movement up and down for alignment.

65 A pin 39 (Fig. 4) having reduced end por-

tions is passed through the actuating rod 30 and through the slot 27 of the stem portion 24, to hold these members in assembled relationship. The central portion is substantially the same length as the thickness of the rounded portion 28 of the rod 30. A spiral spring 40 is coiled about the rounded inner end 24^a of the stem 24 and presents one end over and around the portion 28 of the rod 30 and the central portion of the pin 39 (thereby holding the pin in place) and exerts a relative thrust between this pin 39 and the shoulders at the junction of the rounded and square portions of the stem 24, so that a resiliency is afforded against sudden impact upon the bumper 23 to prevent a breakage of the associated parts, and the engagement of spring 40 against the frame gives a definite limit to the outward movement of the bumper 23.

A groove 42 is formed on the inner face of the bight 22 to receive the corresponding portion of the eye 38 and its guiding rib 38^a which fills the groove 42, whereby the link is caused to act against the inner surface of the eye 38 and the bight 22 without injury to this eye 38, which may consequently be made of relatively light construction. This groove 42 is continued along both the top and bottom of the cavity in the drawhead 18 as the grooves 42^a, 42^b, which receive and guide the eye 38 of the actuating link 37 in its movement. These grooves 42^a, 42^b are wide at the rear or inner end to afford side play and lateral swing for the link L, and converge toward the bight 22 to guide the eye 38 into the groove 42.

The link L itself slides on the floor of the cavity in the link draw-head 18, and is guided laterally by the cheeks 43 of the drawhead 18, and when retracted is returned thereby to a central position as shown in the figures. It will be noted that the link drawhead 18 has its cheeks 43 cut away enough to allow link L to be turned around the axis of the bight 22, so that the link L may be drawn to its extreme outmost position as shown by the dotted lines L_x in Fig. 5, and the link may then be rotated substantially about the center of the bight 22 and slid laterally into a position such as shown by L_y. The link may be slid further and even reversed in position if so desired.

The lever arm ratio of the lever 32 between the separation of pivot pin 33 and the offset of the cam 31 is such that a very slight movement of the bumper 23 will cause a full projection of the link L. This permits the slots 27 and 29 to be short, and allows the spring 40 to absorb or cushion the movement even in case the link L be entirely blocked against movement. The surface of cam 31 is such that this ratio is greatest at the first movement, and successively decreases, so that in conjunction with increasing retardation owing

to the tension of spring 34, the link L moves more and more slowly toward the end of its stroke.

At the end of its movement, the bumper 23 seats itself in a pocket (Figs. 3 and 4) formed in the flange 26, and the final impact of the cars occurs between respective members solidly secured to the car bodies, and the cars may be pushed in train by direct engagement of the drawheads against each other.

The drawhead 20 in Fig. 1 carries the coupling pin parts including the retraction link 60 engaged over the free end of the uncoupling lever 63 having the terminal laterally extending lug 64 to prevent disengagement of the link 60 from the lever 63. The lever 63 is fixed to the actuating shaft 64', which itself is journaled in the clips 65 fastened to the end of the car. A handle 67 is provided in this shaft for manual operation in the usual manner while the cover plate 68 about the stem of the retraction link 60 serves to protect the drawhead 20 against the entry of dirt at its top.

The method of coupling between two cars having the parts as described is as follows:

The car having its link coupling parts in the position shown in full lines in Figs. 4 and 5, the car is brought forcibly against a car having a pin coupling whereby a downwardly extending lip on the pin drawhead encounters the actuating bumper 23 on the link drawhead. The bumper 23 is driven forcibly inward or to the left in Fig. 4, transmitting its movement to the actuating rod 30, which in turn acts upon the surface of the cam 31 of the actuating lever 32, and against the action of the spring 34 causes this lever 32 to rock clockwise about its pivot 33 whereby a thrust is delivered through the actuating link to the corresponding car link L, which is projected forcibly from its drawhead 18. Since this link L is by construction in alignment with the mouth of the pin drawhead 20^b of the other car the link L enters this mouth and encounters the coupling detent therein, so that the pin Pb is allowed to fall by gravity and enter the aperture of the coupling link L. The coupling has now been made, and when the cars are drawn apart in train, the link L will be engaged with the bight 22 on its own drawhead and with the pin Pb on the pin drawhead, whereby the draft stress is transmitted solidly from the draw beam of the one car to the draw beam of the next car, without any undue strain upon the relatively delicate actuating members. During this operation of coupling, if the pin drawhead is blocked, the spring 40 will take up the strain until the cars move away from each other, whereby a breakage of the actuating members is avoided. As soon as the cars separate from each other, the spring 34 will take up the slack in the link L and prevent looseness or rattling

of this member. Further, the shock when the link L encounters the pin coupling detent and drives it to the end of its travel is likewise taken up by the spring 40.

The operation of uncoupling consists merely in raising the pin Pb until it disengages the link L, which is then immediately retracted by its spring 34, and the cars are free from one another.

The link L is afforded great freedom of movement about its bight 22, so that the cars may pass around curves of very short radius, without any blocking by engagement of the link L with the cheek walls 43 of the link drawhead.

It is obvious that the invention is not limited to the specific embodiment shown, but that it may be modified in many ways within the scope of the appended claims.

I claim:

1. In a link and pin coupling, a link drawhead fastened to the end of the vehicle, a coupling link, said drawhead having a cavity therein to receive the link when retracted and including an integral bight passing through the link to receive the draft stresses, the floor of said cavity having a groove therein, an actuating link embracing said coupling link and guided by said groove, and means actuated upon impact with another vehicle to operate said actuating link to project said coupling link.

2. In a pin and link coupling, a link drawhead fastened to the end of the vehicle, a coupling link, a bumper, and devices connected to said bumper to project said link upon impact of another vehicle, said means including a rod and cam mechanism whereby the rate of said projection progressively decreases with increments of movement of said bumper.

3. In a pin and link coupling, a link drawhead fastened to the end of the vehicle, a coupling link, a bumper having an inwardly extending actuating stem with a slot therein, an actuating rod in extension of said stem, a spring engaging said stem and rod to force them normally apart, said rod having an aperture therein in alignment with said slot, a pin in said aperture to limit the movement of separation of said stem and said rod and to guide said stem and said rod in their relative movements, and devices actuated by the movement of said rod to project said coupling link.

4. In a pin and link coupling, a link drawhead fastened to the end of the vehicle, a coupling link, a member on said drawhead to receive the draft stress of said coupling link, and an actuating link to project said coupling link, said member having a groove in its inward face to complement said actuating link and to receive the corresponding portion of the same whereby said actuating link is freed from the draft stress.

5. In a pin and link coupling, a link draw-head, a coupling link in said drawhead, means to retract said coupling link into said drawhead in the absence of draft stress thereon, and a member on said drawhead to cooperate with said coupling link to transmit the draft stress, the cheeks of said drawhead being cut away inward of said member so that said coupling link may be drawn out and rotated about said member to reversed position.
- 10 6. In a pin and link coupling, a link draw-head fastened to the end of the vehicle, a coupling link, a bumper having an inwardly extending actuating stem with a slot therein, an actuating rod in extension of said stem and telescoping therewith, a spring engaging said stem at one of its ends, said rod having an aperture therein in alinement with said slot, a pin in said aperture to limit the movement of separation of said stem and said rod, said spring bearing against the ends of said pin for a relative reaction against said rod, and devices actuated by the movement 15 of said rod to project said coupling link.
- 15 7. In a pin and link coupling, a link draw-head fastened to the end of the vehicle, a coupling link, a bumper having an inwardly extending actuating stem with a slot therein, 20 an actuating rod in extension of said stem and telescoping therewith, said rod having an aperture therethrough in alinement with said slot, a pin projecting through said aperture and slot and having extended end portions and a body portion of substantially the thickness of said rod, a spring engaging at 25 one end against said stem and at the other end fitting over said rod and said body portion and reacting against the extended end portions of said pin, and devices actuated by 30 the longitudinal movement of said stem and rod to project said coupling link.
- 35
